UNITED STATES PATENT OFFICE.

HENRY B. FORD, OF NEW YORK, N. Y., ASSIGNOR TO PERKINS & WELSH, OF SAME PLACE.

CYLINDER FOR AIR-PUMPS AND AIR-COMPRESSORS.

SPECIFICATION forming part of Letters Patent No. 363,453, dated May 24, 1887.

Application filed October 18, 1886. Serial No. 216,106. (No model.)

To all whom it may concern:

Be it known that I, HENRY B. FORD, of the city, county, and State of New York, have invented a new and useful Improvement in Cylinders for Air-Pumps and Air-Compressors, of which the following is a specification.

My invention relates to a novel construction of the piston, piston-rod, and jacket of the cylinders of air or other gas compressors, whereby water is caused more efficiently to circulate through said rod, piston, and jacket for the purpose of cooling said parts.

My invention consists in the construction and arrangement of the mechanism as more particularly hereinafter set forth.

In the accompanying drawings, Figure 1 is a longitudinal section of my apparatus, and Fig. 2 is a transverse section on the line *x x* of Fig. 1.

20 Similar letters of reference indicate like parts.

A is the compressor-cylinder. B is a piston in said cylinder. C is the piston-rod. D is the water-jacket surrounding the cylinder A. The piston and piston-rod are made hollow. Outside of and communicating with the water-jacket D is a small auxiliary pump-cylinder, E. This pump has also a hollow piston, F, and a hollow piston-rod, G. Piston-rod G is rigidly connected by a tubular connection, H, in any suitable way with the main piston-rod C; hence the piston F moves in its cylinder E simultaneously with the movement of the piston B in the cylinder A. Of course, if it be desired that the piston F shall have a shorter stroke than the piston B, any suitable reducing-gear may be used to convey motion from the main to the auxiliary piston-rod, and in such case the tube H may be made of rubber or any othersuitable flexible material. In my present drawings I show, however, that the piston F has a stroke equal in length to that of piston B, a break being made across both cylinders A and E to indicate this. The small piston F is hollow, and has a valve, I, which opens inwardly.

J is a pipe entering the small cylinder E. K is a valve opening into said cylinder.

L is a valve opening into the pipe M, which

passes into the water-jacket D, and nearly to 50 the end of the same.

The valves I, K, and L are here shown as simple clap-valves; but of course they may be of any other known construction.

Within the main piston-rod C is a pipe, N, 55 which passes through said rod and communicates with the interior of the piston B. O is an opening between the interior of said piston and the annular space P in the piston-rod enclosing the pipe N. The outer end of the piston-rod C is closed. A break is shown in the rod C to indicate that the pipe N here extends through its whole length. Said pipe may be provided with a flexible extension at Q, which will not interfere with the reciprocation of the 65 piston-rod. R is a stuffing-box of ordinary well-known construction.

The operation of the above-described mechanism is as follows: When the piston B is moving outward—that is, from left to right in the drawings—the piston F in cylinder E moves in the same direction. The valve in said piston then closes, the valve K opens and the valve L shuts. Water is then drawn into the cylinder E. On the return-stroke of the main piston B—that is, from right to left in the drawings—the piston F moves in the same direction. The valve K then shuts and the valves I and L open. Consequently the water which has been drawn into the cylinder E 70 is now forced part through the tube M into the water-jacket D, through which it circulates and escapes by a pipe, (not shown) and part through the hollow piston G, whence it passes into the annular space P in the main 75 piston-rod C. From the rod C the water passes through the opening O into the piston B, and from said piston into the tube N, and finally out at the tube Q.

It will be apparent that the result of this 80 construction is to insure a constant circulation of water both through the jacket and through the pump piston and rod at each stroke, and hence a very efficient cooling of the adjacent parts of the mechanism during the work on 85 compression is caused.

I claim—

A water-jacketed main cylinder and a hol-

low piston and piston-rod therein, combined with an auxiliary pump-cylinder having a valvular connection with a water-supply, and also with the water-jacket of the main cylinder, a hollow valvular piston in said auxiliary pump-cylinder, and a hollow piston-rod therefore, connected with the hollow piston-rod of the main cylinder, and moving therewith to

supply the jacket with water and force the water into and out of the main piston, substantially as described.

HENRY B. FORD.
